F.W.Brockslper

Inventor

United States Patent Office.

W. BROCKSIEPER, OF NEW HAVEN, CONNECTICUT, ASSIGNOR TO SARGENT AND COMPANY, OF SAME PLACE.

Design No. 3,024, dated May 12, 1868.

DESIGN FOR A BRACKET.

The Schedule referred to in these Letters Patent and making part of the same.

ALL WHOM IT MAY CONCERN:

Be it known that I, F. W. BROCKSIEPER, of New Haven, in the county of New Haven, and State of Connecticut, have invented a new Design for a Bracket; and I do hereby declare the following, when taken in connection with the accompanying drawing, to be a full, clear, and exact description of the same, and which said drawing constitutes part of this specification, and represents a perspective view.

This invention relates to a design for a wall-bracket, formed from cast metal, in imitation of carved wood. The shelf represents an oak-branch, and the base is formed from the branches of an oak-tree, represented as growing from an earth base. A boy is watching a bird, near its nest, at the trunk of the tree; all as shown in the accompanying illustration.

Having described my invention, what I claim as new, and desire to secure by Letters Patent, is—
The design for a bracket, as herein described and illustrated.

F. W. BROCKSIEPER.
